UNITED STATES PATENT OFFICE.

CHARLES WEBER, OF WEST MERIDEN, CONNECTICUT.

IMPROVED TABLE-MAT.

Specification forming part of Letters Patent No. **55,402**, dated June 5, 1866.

To all whom it may concern:

Be it known that I, CHARLES WEBER, of West Meriden, county of New Haven, State of Connecticut, have invented a new and Improved Table-Mat; and I do hereby declare that the following is a full, clear, and exact description thereof, enabling those skilled in the art to fully understand and use the same, reference being had to the accompanying drawings, in which—

Figure 1 represents a plan or top view of this invention. Fig. 2 is a longitudinal vertical section of the same.

Similar letters of reference indicate corresponding parts.

This invention relates to a table-mat which is provided with a metal frame in such a manner that by the metal rim the body of the mat is strengthened and prevented from warping.

The body of the mat is made of pasteboard, prepared with oil and varnish and backed, so as to form papier-maché, and it is finally covered with cloth, leather, or other suitable material and framed, so that a table-mat is obtained which is capable of resisting heat and moisture, and which is strong, durable, and of elegant appearance.

A represents a table-mat which is made oval, round, polygonal, or of any desired form or

shape, and provided with a metal frame, B, which embraces the edge of the mat and serves to strengthen and stiffen the same, so that it is not liable to warp when exposed to heat or moisture, or both combined.

The body of the mat I make of pasteboard, which is prepared with oil and varnish, and backed, so as to form papier-maché. It is then covered with cloth, leather, or other suitable material, and a table-mat is obtained which is strong and durable and which is not liable to warp under the most adverse circumstances.

It must be remarked, however, that the metal frame is applicable to table-mats made of any other suitable material; but I use by preference pasteboard prepared as above described, because such a mat is cheap and of superior strength and durability.

What I claim as new, and desire to secure by Letters Patent, is—

A table-mat made as herein described and provided with a metal frame, substantially as and for the purpose specified.

The above specification of my invention signed by me this 2d day of April, 1866.

CH. WEBER.
